Filed May 1, 1961, Ser. No. 64,992

Term of patent 14 years

(Cl. D81—25)

FIG. 1

FIG. 2

FIG. 3

FIG. 4

FIGURE 1 is a perspective view of a handle for kitchen ranges or the like embodying my new design;

FIGURE 2 is an enlarged, fragmentary, rear elevational view of one extremity of the handle;

FIGURE 3 is an enlarged end elevational view of the handle; and

FIGURE 4 is an enlarged top plan view of one extremity of the handle.

The characteristic features of my design for the handle disclosed reside in the combined cap and anchor units positioned at the ends thereof as shown.

I claim:

The ornamental design for a handle for kitchen ranges or the like, as shown and described.
